UNITED STATES PATENT OFFICE.

EMORY CROUSE, OF WICHITA, KANSAS.

SUPPORTING FRAME FOR LIQUID-DISPENSING APPARATUS.

Application filed October 30, 1922. Serial No. 597,902.

To all whom it may concern:

Be it known that I, EMORY CROUSE, a citizen of the United States, residing at Wichita, county of Sedgwick, and State of Kansas, have invented certain new and useful Improvements in Supporting Frames for Liquid-Dispensing Apparatus; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to an improvement in liquid dispensing apparatus and has special reference to the supporting framework thereof.

It is becoming an almost universal custom to dispense gasoline by means of a dispensing apparatus having a glass container at its top into which the gasoline is pumped and from which it flows into the gasoline tank of the automobile by the action of gravity. One form of liquid measuring and dispensing apparatus of the type referred to is described in my co-pending application Serial No. 538,171, filed February 21, 1922.

The object of this invention is to produce a simple and substantial framework for the purpose of holding the measuring reservoir in its elevated position. My invention in its broadest aspect consists in employing the supply and overflow pipes for the supporting member.

In order to more clearly describe my invention, I shall have reference to the accompanying drawing, which shows my invention incorporated in three specifically different types of dispensers, and in which—

Fig. 1 is a side elevation partly in section of a dispenser embodying my invention and employing compressed air for the purpose of elevating the liquid to the reservoir;

Fig. 2 shows my invention embodied in a dispenser employing a rotary hand operated pump for the purpose of elevating the liquid; and

Fig. 3 shows a device similar to that shown in Fig. 2, but employing an electric motor to elevate the liquid to the reservoir.

The same reference numerals will be employed to designate the same parts throughout the several views.

Numeral 1 represents the base ring, which

has an upwardly extending annular flange 2, against which the steel housing 3 rests. A bracket 4 is cast integral with the base ring 1, or may be made in a separate piece and secured thereto by rivets. The bracket is provided with upwardly extending tubular members 5 and 6, which are adapted to receive respectively the overflow pipe 7 and the supply pipe 8. A glass bowl base 9 having a downwardly extending flange 10 serves to receive the upper end of the steel housing 3. The glass bowl base has a bottom 11, through which the pipes 7 and 8 extend and which is connected to the latter in any suitable manner, as by being threaded thereonto. An annular upwardly extending flange 12 serves to support the glass measuring bowl 13. The supply pipe 8 extends into the bowl 13 and is provided with means, not shown, for causing the liquid to enter the bowl near the bottom thereof. The overflow pipe 7 extends upwardly into the bowl to the level of the liquid when the bowl is filled to its maximum capacity, which is usually five gallons. The gasoline or other liquid may be transferred from the underground storage tank by any desirable means, such as a hand pump, an electrically operated pump, or by compressed air. The dispenser shown in Fig. 1 is provided with compressed air means for elevating the gasoline, but as this forms no part of my present invention, I shall not describe the same further than to say that 14 represents the air controlling valve.

In Fig. 2, 15 represents a rotary hand pump connected in series with the supply pipe 8, and in Fig. 3 I have shown a rotary pump 16 which is driven by a motor 17 through the medium of a chain 18. A drain pipe 19 (Fig. 1) is connected to the overflow pipe at 20 and is provided with a central valve 21. A pipe 22 connected to the pipe 19 just below the bottom 11 is connected to the dispensing hose (not shown). In Figs. 2 and 3 I have shown a meter 23 connected between the drain pipe 19 and the hose connection 22. The pipes 7 and 8 are made of substantial size so as to have the requisite strength and serve as the main framework for supporting the dispensing bowl 13 and the base 9 upon which it rests. When the steel housing 3 is put in place, it will add to the rigidity of the structure, but it is not depended upon and can be entirely removed if desired. The pipes 7 and 8 form

the supporting framework and therefore perform a double function.

It is evident from the above that I have produced a dispensing apparatus that is so 5 designed that the supply and the overflow pipes thereof constitute the supporting members of the framework, and that the cost of the resultant structure is therefore greatly reduced, as these pipes must be employed even if other means were employed 10 to support the measuring bowl, and by making them serve as a framework a much simpler construction results.

Having now described my invention, what 15 I claim as new is:

1. A liquid dispensing and measuring apparatus comprising in combination a base ring adapted to be secured to a foundation, a bowl supporting base and means for

rigidly spacing said base ring and said bowl 20 supporting base, said means consisting of the supply and the overflow pipes.

2. A liquid dispensing and measuring apparatus comprising in combination a base ring adapted to be secured to a foundation, 25 a transverse bracket secured thereto, said bracket having upwardly extending tubular portions adapted to receive the supply and the overflow pipes, means carried by said tubular portions for clamping said pipes in 30 place, a bowl supporting base and means for securing said base to the pipes at a point above said base ring, whereby said pipes will serve to hold the latter in place with respect to the base ring.

In testimony whereof I affix my signature.

EMORY CROUSE.
